UNITED STATES PATENT OFFICE

171,198

MILK EVAPORATOR UNIT

Albert W. Eckstrom, Buffalo, N. Y., assignor to
Blaw-Knox Company, Pittsburgh, Pa., a corporation of Delaware

Application December 22, 1952, Serial No. 22,819

Term of patent 14 years

(Cl. D16—2)

To all whom it may concern:

Be it known that I, Albert W. Eckstrom, a citizen of the United States of America and residing at Buffalo, in the county of Erie and State of New York, have invented a new, original, and ornamental Design for a Milk Evaporator Unit, of which the following is a specification, reference being had to the accompanying drawings forming part thereof.

Fig. 1 is an elevational view of the front of a milk evaporator unit embodying my new design.

Fig. 2 is a top plan view thereof.

Fig. 3 is a rear elevational view thereof.

Fig. 4 is a bottom plan view thereof.

Fig. 5 is an end elevational view viewed from the right of Fig. 1.

Fig. 6 is an end elevational view viewed from the left of Fig. 1.

I claim:

The ornamental design for a milk evaporator unit, substantially as shown.

ALBERT W. ECKSTROM.
